P. FRANTZ

PROCESS OF MAKING HINGES

Filed Dec. 5, 1921

Inventor
Peter Frantz

by Arthur F. Durand Atty

UNITED STATES PATENT OFFICE.

PETER FRANTZ, OF STERLING, ILLINOIS, ASSIGNOR TO FRANTZ MANUFACTURING COMPANY, OF STERLING, ILLINOIS, A CORPORATION OF ILLINOIS.

PROCESS OF MAKING HINGES.

Application filed December 5, 1921. Serial No. 520,060.

To all whom it may concern:

Be it known that I, PETER FRANTZ, a citizen of the United States, and a resident of Sterling, county of Whiteside, State of Illinois, have invented a certain new and useful Improvement in Processes of Making Hinges, of which the following is a specification.

This invention relates to the manufacture of hinges for doors or for other purposes, and it relates more particularly to hinges of that particular form in which two plates are held together by a pintle, with pintle bearings forming a knuckle joint between the two plates, whereby at least one plate is provided with a space formed to receive the other plate.

Generally stated, therefore, the object of the invention is to provide an improved method of blanking out the hinge plates from sheet metal, in a manner that not only insures against waste, but also in a manner that renders the hinge satisfactory in use, as will hereinafter more fully appear.

To these and other useful ends the invention consists in matters hereinafter set forth and claimed and shown in the accompanying drawings in which:

Figure 1 is a plan of a strip of sheet metal showing diagrammatically the method of blanking out the hinge plates by a method or process involving the principles of the invention.

Figure 2 is a plan of an ordinary so-called T-hinge made in accordance with the invention.

Figure 3 is a perspective of one of the hinge plates formed by the blanking method shown in Figure 1.

As thus illustrated, the invention comprises a sheet metal hinge plate 1 formed as shown in Figure 3, having the portions 2 thereof rolled or bent to form the pintle bearings 3 shown in Figure 2, and having holes 4 for screws or other attaching means. It will be seen that the combined width of the portions 2 is equal to the width of the space 5 between them, so that the blanking method shown in Figure 1 is possible. With this method, as shown, each space 5 is formed by cutting out metal enough to form the two end portions 2 of two different plates. The holes 4 are punched at the same

time that the plates are punched out from the long strip of sheet metal, it being observed that this strip travels in the direction indicated by the arrow, so that the portions 2 extend crosswise or at right angles to the length of said strip. In this way, therefore, it will be seen that no metal is wasted, as the spaces 5 in the plates are formed by cutting out enough metal to form the portions 2 of said plates.

The plates thus formed can be combined with other plates in any suitable or desired manner, in order to form hinges of the required character. As shown in Figure 2, the long plate 6 is formed with a pintle bearing 7 to fit in the space 5 of the plate 1, and a pintle of any suitable character is inserted in the bearings 3 and 7 to hold the plates together, thus forming what is ordinarily called a T-hinge. Obviously, however, the hinges formed may be of any suitable size or style, but in any event, and regardless of the design employed, the pintle bearing 7 is equal in length to the combined length of the bearings 3, so that the knuckle of the hinge has the metal thereof divided equally between the two plates. Thus the feature of having the combined width of the portions 2 equal to the width of the space 5, in blanking out the plates, not only tends to insure against unnecessary waste in the cutting of the sheet metal, but also ensures or brings about some advantageous and desirable results in the use of the hinge, as well as in the making of hinges of different sizes. When the combined width of the portions 2 is equal to the space 5, hinges of different sizes can be made by simply using sheet metal strips of different widths, and by cutting each sheet in the manner shown in Figure 1, whereby plates of different sizes will be made or produced.

It will be seen that the articles formed during the blanking operation have all their edges formed on straight lines extending at right angles to each other so that each article is substantially rectangular except for the space 5 formed in one side edge thereof.

What I claim as my invention is:

1. The process of making a hinge, comprising the blanking and cutting of sheet metal to form plates each having a space occupied during the blanking operation by

the end portions of two other plates, so that the metal cut out to form the space of each plate is utilized to form the end portions of other plates, thereby to prevent waste in the cutting of the metal.

2. A process for making hinges of the kind comprising a plate having pintle bearings spaced apart a distance equal to the combined length of said bearings, so that 10 each bearing is equal to one-half of the width of said space, and another plate having a pintle bearing adapted to fit in said space, whereby said last mentioned pintle bearing is equal in length to the combined 15 length of said first mentioned pintle bearings, comprising the formation of said first mentioned pintle bearings from metal cut away to form a space between two similar bearings of another plate of the same size and form, 20 thereby to prevent waste in the cutting of

the metal from which the plates of this kind are made.

3. The process of blanking out sheet metal articles, each article having two end portions spaced apart a distance equal to the 25 combined width of said end portions, comprising the formation of said end portions from the metal cut away to form the space of each plate, whereby no waste metal occurs anywhere between the plates during the 30 blanking operation.

4. A process as specified in claim 3, in which said articles are formed with all their edges on straight lines at right angles to each other.

5. A process as specified in claim 3, in which the sheet metal is in the form of a long strip having said end portions extending at right angles to the length thereof.

35
PETER FRANTZ.
